CLAIM

The ornamental design for a foldable game board with fastener for tic tac toe, as shown and described.

DESCRIPTION

FIG. 1 is a perspective view showing the foldable game board with fastener for tic tac toe in a folded configuration embodying my new design;

FIG. 2 is a perspective view showing the foldable game board with fastener for tic tac toe in an open configuration embodying my new design;

FIG. 3 is a front view of the open configuration thereof;

FIG. 4 is a back view of the open configuration thereof;

FIG. 5 is a right side view of the open configuration thereof;

FIG. 6 is a left side view of the open configuration thereof;

FIG. 7 is a front end view of the open configuration thereof; and,

FIG. 8 is a rear end view of the open configuration thereof.
